Patented Nov. 9, 1920.

UNITED STATES PATENT OFFICE.

CHARLES L. CLARK, EDWARD H. PERKINS, AND CLAUDE S. WE METT, OF WAYLAND,
NEW YORK.

VALVE-SPRING COMPRESSOR.

1,357,954.

Specification of Letters Patent.

Patented Nov. 9, 1920.

Application filed January 28, 1920. Serial No. 354,541.

To all whom it may concern:

Be it known that we, CHARLES L. CLARK, EDWARD H. PERKINS, and CLAUDE S. WE METT, citizens of the United States, residing at Wayland, in the county of Steuben, State of New York, have invented a new and useful Valve-Spring Compressor, of which the following is a specification.

This invention has reference to improved valve spring lifters, and it is the primary object of the invention to provide a spring lifter which will compress the usual controlling spring, to permit the valve to be readily and easily removed.

15 A further object of the invention is to provide a device of this character which may be adjusted to operate on valves of various sizes, the device having means to permit of unlimited adjustment.

20 A further object of the invention is to provide a valve spring compressor which may be readily folded into a small compact article to permit the device to be easily carried within the usual tool box.

25 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

30 Referring to the drawings:—

Figure 1 illustrates a side elevational view of a valve spring compressor constructed in accordance with the present invention.

35 Fig. 2 illustrates a side elevational view disclosing the same in its folded position.

Fig. 3 illustrates a rear elevational view thereof.

40 Fig. 4 illustrates a detail view of the connecting links, taken on line 4—4 of Fig. 1, and

Fig. 5 illustrates a fragmental plan view of the lower spring engaging arm.

45 Referring to the drawing in detail, the body of the device includes opposed arms 5 and 6, each of which is provided with a band 7 adapted to embrace a portion of the opposed arm to permit of free and easy

movement of one arm, longitudinally of the opposed arm.

55 Each of these arms 5 and 6 is formed of suitable metal, the side edges thereof being substantially square so that the square ends of the arms 8 and 9 may closely engage the side edges of the arms 5 and 6 in a manner to prevent lateral displacement, of the arms 8 and 9 with relation to the arms 5 and 6.

60 Disposed at the outer end of the arm 8 is a valve engaging finger 10, the lower extremity of which is pointed as at 11 so that the finger 10 may engage within the usual groove formed in the valves, now in use, thereby insuring against movement of the finger 10 with relation to its valve, in one direction.

65 This valve engaging finger 10 is pivoted to the arm 8 as at 12, a cut out portion 13 being provided adjacent the upper edge of the finger 10, which cut out portion provides a shoulder to contact with the pin 14, secured to the arm 8 and extending laterally therefrom, so that the finger 10 is restricted 70 from moving outwardly from the arms 5 and 6, but permitted to move to a position overlapping the arm 8, when the device is 75 folded.

75 The lower arm 9, which co-operates with the arm 8 for accomplishing the compressing result, has its outer extremity twisted to provide a relatively flat surface 15, which is slotted as at 16 to straddle a portion of the valve rod, of the valve under operation.

80 Associated with the arms 8 and 9 are the connecting links 17 and 18, which have one of their respective ends rigidly secured to the bars 8 and 9 by means of the bolts 19, and as shown, the upper connecting link 17 is pivotally connected to the operating handle 20, as at 21, the operating handle 20 also being pivotally connected to the operating rod 22, by means of the removable pin 23 adapted to be positioned in one of the openings 24, provided on the operating rod 22. From the foregoing it is obvious that due to the spaced relation of the openings 24, an appreciable adjustment may be had, between the operating rod 22 and the operating handle 20, thus adapting the device for use in connection with valves of various sizes.

85 100 105 The lower end of the operating rod 22 has

connection with the connecting link 18 by means of the bolt 25, so that movement of the operating rod 22 causes a relative movement of the arm 6, since the bolt 25 passes through the arm 6, to rigidly connect the same with the lever 22.

It might be further stated that the connecting bolt which connects the operating lever 20, to the connecting link 17 also extends through the opening provided in the arm 5, so that movement of the operating handle 20 causes the arms 5 and 6 to slide with relation to each other, to bring the arms 8 and 9 toward and away from each other, according to the direction in which the operating handle 20 is moved.

In the operation of the device, the valve engaging finger 10 is positioned on the valve under operation, and the slotted end 20 of the arm 9 is positioned to straddle the valve rod. The operating handle 20 is now moved to a position as indicated in Fig. 1 of the drawing with the result that the arms 5 and 6 are moved with relation to each other, to bring the arms 8 and 9 closer together.

It follows that the coiled spring usually embracing the valve stem, and which has one of its extremities contacting with the upper 30 surface of the arm 9, is compressed, relieving the valve proper of the tension of the coiled spring.

Having thus described the invention, what we claim as new is:—

1. In a valve spring lifter, a pair of opposed arms, means for moving the opposed arms with relation to each other, each of said arms having a horizontally disposed arm pivotally connected thereto, a valve engaging finger pivotally connected to one of said horizontally disposed arms, and means for connecting the arms to permit the same to be moved to a position in parallel relation with each other. 35

2. In a valve spring lifter, a pair of opposed arms, means for slidably connecting the arms, a pair of horizontally disposed arms having connection with the opposed arms, a valve engaging finger pivotally supported by one of said horizontally disposed arms, the opposite horizontally disposed arm having a slotted portion adapted to embrace a valve stem, and means for moving the first mentioned arms with relation to each other. 40

In testimony that we claim the foregoing as our own, we have hereto affixed our signatures in the presence of two witnesses.

CHARLES L. CLARK.

EDWARD H. PERKINS.

CLAUDE S. WE METT.
